COMBINED LEAD PENCIL HOLDER OR PROTECTOR AND SHARPENER

Egil Johan Havnen, Oslo, Norway

Application December 19, 1947, Serial No. 792,818
In Norway February 13, 1946.

3 Claims. (Cl. 120—93)

1

The present invention relates to a combined lead pencil holder or protector and sharpener of the type comprising two tubular members slidable on one another, of which members one is provided with a conical sharpener at one end and the other with a holding device for the lead pencil, and the object of the invention is to provide a lead pencil holder being both comfortable when the pencil is in use and adapted to be carried in the pocket, as well as providing a proper guide during sharpening and automatic adjustment of the sharpening.

According to one feature of the invention the two tubular members of the pencil holder are provided with external and internal screw threads respectively, adapted to engage one another with such very small pitch that the pencil is advanced or fed against the sharpening device at a suitable rate by relative turning movement of the said members. In order to prevent an unrequired amount of the lead pencil being cut away during the sharpening, the lengths of the portions of the said tubular members forming screw threads may be so dimensioned relatively to each other that the said members are disengaged, and consequently the feeding of the pencil discontinued, when the required sharpening is completed.

In order to reduce the dimensions of the sharpening device proper it may conveniently be made in the form of a steel cone, the wall of which is provided with at least one helically extending slot having one side edge turned radially inwardly and sharpened so as to form a knife edge of the sharpening device. Due to the fact that the said knife edge is extending helically the sharpening action of the same is improved as compared with such known conical sharpeners having the usual straight knife edges. The device according to the present invention may, however, alternatively be provided with a sharpener having a straight knife edge which is turned inwardly in the manner stated, or again alternatively formed by a distinct steel knife secured as by screwing along the length of a slot in the cone, as conventional in known conical sharpeners.

According to another feature of the present invention the sharpener is detachably secured to the outer of the said two tubular members, being for instance provided with screw threads adapted to engage corresponding screw threads in the said member, the said co-operating screw threads being of an opposite pitch as compared with the screw threads interengaging the said two tubular members.

According to a further feature of the present invention a tube or casing which is closed at one end may be detachably secured to the outer of the said two tubular members, the said tube or casing enclosing the sharpener so as to give the holder an ideal smooth cylindrical form. The said tube or casing also serves to receive chips formed during sharpening and may be detached and emptied from time to time.

10 On the accompanying drawing an embodiment of the device according to the present invention is shown, the figure being an axial sectional view.

In the drawing the combined device according to the invention is shown without any pencil received in the same, and with the inner and outer tubular members disengaged from each other, 1 being the inner tubular member and 4 the outer tubular member.

The member 1 is provided with a holding device for the lead pencil, which device in the embodiment shown is formed of tongues or hooks 2 which are struck up from the wall of the member and are bent inwardly springlike so as to effect a holding action on a pencil received in the member, but obviously other suitable holding arrangements of any type may be employed when convenient. At the lower end of the tubular member 1 there are provided external screw threads 3.

The outer tubular member 4 is provided with internal screw threads 5 extending over an intermediate portion of its length and being engageable with the screw threads 3 on the inner member 1 when the said two tubular members are slid one into the other. The lower end of the tubular member 4 is provided with interior screw threads 6 which may be engaged by corresponding screw threads 6' on the sharpening device 7, thereby securing the said device to the outer tubular member 4. The said screw threads 6 are made with an opposite pitch as compared with the screw threads 3 and 5. The tubular member 4 is also provided with exterior screw threads 8 adapted to be engaged by corresponding screw threads 8' on the casing or tube 9.

45 The conical wall of the sharpening device 7 is provided with a helically extending slot 10, one side edge of which is turned inwardly so as to form the sharpening knife edge.

When a pencil is to be sharpened, the tubular member 1 is first introduced into the tubular member 4 until the screw threads 3 and 5 are just brought into engagement with one another, whereupon the lead pencil is pushed into the tubular members to such extent that the point 55 of the pencil is abutting against the sharpener.

The tubular members are then rotated relatively to each other and the pencil is then, due to the fact that it is kept in the member 1 by means of the devices 2, automatically advanced towards the sharpener in accordance with the pitch of the screw threads 3 and 5 and is thereby sharpened by the knife edge of the slot 10, the pencil being thereby positioned by the guiding action of the member 1 in the member 4. The feeding movement is continued as long as the screw threads 3 and 5 are interengaged, but is automatically discontinued when the screw threads 3 have passed all through the screw threads 5. When the lead pencil is to be used, it is withdrawn from the tubular members 1 and 4 and reintroduced with the outer end, the point being then turned outwardly, ready for use.

In order that the lead pencil holder may be more comfortable to keep in the hand, it may be provided with external grooves or the like, for instance on the truncated-conical end portion 11 of the tubular member 1 and on a portion of the casing or tube 9.

The special manner of securing the sharpener proper to the outer tubular member by means of the interengaging screw threads 6 and 6' makes it possible to construct the sharpener in two substantially similar halves which at their upper end are held together by being embraced by the tubular member and at their lower end by means of a ring or nut. Such subdivision of the sharpener is of a special advantage in the production and by later sharpening of the cutting edge of the same.

What I claim is:

1. A combined lead pencil holder, protector and sharpener comprising two tubular members which are slidable one in the other, one of the tubular members being provided with a holding device for the lead pencil and the other tubular member with a conical sharpening device, the said tubular members being provided with cooperating screw threads of very small pitch so as to feed the lead pencil against the sharpening device by relative rotation of the said tubular members.

2. A combined lead pencil holder, protector

and sharpener comprising two tubular members which are slidable one in the other, one of the tubular members being provided with a holding device for the lead pencil and the other tubular member with a conical sharpening device, the said tubular members being provided with cooperating screw threads of very small pitch so as to feed the lead pencil against the sharpening device by relative rotation of the said two tubular members, the portions of the tubular members provided with screw threads being of such lengths that the screw threads come out of engagement and the feeding of the pencil is discontinued upon a certain axial movement of the two tubular members relatively to one another.

3. A combined lead pencil holder, protector and sharpener comprising two tubular members which are slidable one in the other, one of the tubular members being provided with a holding device for the lead pencil and the other tubular member with a conical sharpening device, the said tubular members being provided with cooperating screw threads of very small pitch so as to feed the lead pencil against the sharpening device by relative rotation of the said two tubular members, the conical sharpening device being secured to the end of the outer of the two tubular members, being provided with external screw threads with which it is screwed into internal screw threads in the end of the said outer tubular member.
